UNITED STATES PATENT OFFICE.

HARRY WAYNE WHITE, OF EMPORIA, KANSAS.

WASHING-MACHINE.

1,378,925.

Specification of Letters Patent. Patented May 24, 1921.

Application filed March 18, 1920. Serial No. 366,771.

To all whom it may concern:

Be it known that I, HARRY WAYNE WHITE, a citizen of the United States, and a resident of Emporia, in the county of Lyon and State of Kansas, have invented certain new and useful Improvements in Washing-Machines, of which the following is a specification.

My invention is an improvement in washing machines, and has for its object to provide a machine of the character specified having a sediment collecting means in the form of a hopper bottom and a perforate plate above the bottom for supporting the clothes out of contact therewith together with a detachable receptacle below the bottom and to which the bottom delivers, the bottom having a baffle plate at the point of delivery.

20 In the drawings:

Figure 1 is a section on the line 1—1 of Fig. 2; and

Fig. 2 is a section on line 2—2 of Fig. 1.

In the present embodiment of the invention the casing 1 of the washing machine has a hopper or funnel-shaped bottom 2 provided with a central opening 3, and the machine casing 1 has a false bottom 4, which is a perforate plate plane and arranged in horizontal position. This plate or false bottom 4 rests at its edge upon the hopper or funnel-shaped bottom at its connection with the body of the casing, and a baffle plate 5 in the form of a disk is supported above the opening 3 midway between the said opening and the false bottom.

The plate 5, which is in the form of a disk, is supported by angle brackets 6 which are secured to the funnel-shaped bottom of the casing. Each of these brackets consists of a portion connected to the casing bottom by a bolt and nut 7, and a laterally offset portion which is secured to the baffle plate by the rivet 8—8. The baffle plate 5 is spaced slightly above the bottom 2 of the machine casing 1, at its edges as will be evident from an inspection of Fig. 2, a sufficient distance to permit the passage of sediment which is carried through the openings of the false bottom 4.

A receptacle is arranged below the bottom 2, the said receptacle consisting of an up-

per section 8 in the form of a ring and a lower section 10 in the form of a cup. These sections have flanges 11 and 12, respectively, 55 which lap upon each other and they are connected together by eye bolts 13, each of these bolts has its eye pivoted to a radial lug 14 on the lower section, and each eye bolt is adapted to be swung upwardly in registering slots in the flanges 11 and 12 and to be engaged by a wing nut to clamp the sections together.

The upper section 8 has a marginal flange 16 which fits against the lower face of the 65 bottom 2 of the machine casing, and is secured thereto by rivets 17, as shown, and the joint at this point is a water-tight joint.

The lower section 10 has a drain outlet 18, which is controlled by a valve 19.

In operation, when the casing 1 is filled with water in the usual manner, the sediment receptacle 8—10 being also full of water, the clothes are supported on the false bottom 4 and the dirt that is removed from them through the openings of the false bottom will be deflected down through the bottom 2 through the openings into the receptacle 8—10. The baffle plate is removable to permit it to be cleaned as is also the screen 75 or false bottom 4. The sediment in the collecting basin 8—10 may be drawn off through the drain pipe 18.

With reference to Fig. 1 it will be observed that sediment received within the receptacle 10 is not disturbed by the eddies which may be created in the receptacle 1 as the result of the operation of the agitator. In other words movement of the water in the upper cleaning receptacle will not agitate the sediment trapped within the sediment receiving receptacle 10. By this means the sediment upon passing through the opening 3 enters the receptacle 10 and remains there undisturbed until completion 80 of the washing operation.

I claim:

1. In a washing machine, the combination with a casing having a funnel-shaped bottom provided with a central opening, of a false perforate bottom for supporting the clothes arranged with the casing, a sediment collecting basin to which the funnel-shaped bottom delivers, and a baffle plate supported 100

above the opening in the funnel shaped bottom, said collecting basin consisting of a section fixed to the bottom of the casing and a section detachably connected with the first-
5 named section.

2. A washing machine comprising a receptacle having a funnel shaped bottom pro-

vided with a discharge opening, a baffle extending over said opening in spaced relation to said bottom, and a sediment receiving and trapping receptacle arranged beneath said opening and having its upper end closed by said funnel shaped bottom.

HARRY WAYNE WHITE.
